UNITED STATES PATENT OFFICE.

DAVID T. OWEN, OF CLEVELAND, OHIO, ASSIGNOR TO THE D. T. OWEN COMPANY,
OF CLEVELAND, OHIO, A CORPORATION OF OHIO.

COMBINED BED AND COUCH.

No. 871,180.

Specification of Letters Patent.

Patented Nov. 19, 1907.

Application filed June 5, 1906. Serial No. 320,328.

To all whom it may concern:

Be it known that I, DAVID T. OWEN, a citizen of the United States, residing at Cleveland, in the county of Cuyahoga and State of Ohio, have invented certain new and useful Improvements in Combined Beds and Couches, and do declare that the following is a full, clear, and exact description of the invention, which will enable others skilled in the art to which it appertains to make and use the same.

My invention relates to improvements in combined beds and couches, and the improvement consists in the construction and arrangement of parts, all substantially as shown and described and particularly pointed out in the claims.

My object is embodied in a convertible piece of furniture adapted to fold and unfold to provide either a bed or a couch and wherein the bed and the couch-seat have separate spring sections each adapted to its own particular use. This latter feature provides for comfort, cleanliness and durability in the use of the device in either of its forms. The question of practical proportions also enters into the making and use of a convertible article of this kind, as it is highly desirable to have the couch of proper length, width and height, as well as to produce a bed of the right length, width and height. Simplicity of operation is also a factor to be considered, as well as stability and safety in use, and I have provided for each and all of these requirements in the construction as hereinafter more specifically described.

In the accompanying drawings Figure 1 is a perspective view of my improved bed and couch as it appears as a couch. Fig. 2 is a larger view in cross section of the couch as shown in Fig. 1, and showing a dotted line position of the parts partly unfolded. Fig. 3 is a cross section of the couch frame with an end view of the bed and seat shown in full lines, in one of the positions assumed, and in dotted lines as down for use as a bed. Fig. 4 is a perspective view of one end of the couch seat and bed frame, and Fig. 5 is a perspective view of a portion of the couch frame showing the socket for the bed pivot.

The couch frame is designated by 2 and comprises ends 3 and side rails 4 with an upholstered back 5 pivotally connected at

a to the upright standards at the rear of ends 3. Back 5 is pivoted to permit it to be raised so that the seat may be unfolded and serves to conceal the fixed legs on the seat, all as hereinafter more specifically described.

Now, referring to the seat, it will be seen that the same comprises a frame 6 adapted to form the main bed frame section and for convenience of description the said frame is hereinafter described as a bed frame and the seat is designated by 7 and the bed mattress by 8. A central division wall 9 of slats or metal frame work divides frame 6 into upper and lower halves and seat 7 has its coiled springs 10 mounted in the upper half, and the bed mattress has springs 12 of its own in the lower half. A cover of upholstering 13 finishes seat 7 at its top and sides.

A supplemental bed section 14 is hinged at 15 upon the ends of frame 6, and this section occupies the space between side rails 4 and is concealed from view except when used as a bed. It will be noted that section 14 is of less width than the other sections and of less width than the inside of couch frame 2 whereby a lateral movement of this section within frame 2 is made possible during folding and unfolding.

Frame 6 has pivot lugs 16 at each end and at the front of the couch, and these lugs are preferably located centrally between the top plane of seat 7 and the sleeping plane of bed mattress 8.

Hinge pivots 15 of bed section 14 are on the same front side of frame 6 as pivot lugs 16 and in the same vertical plane, but this need not be their exact location but preferably so because it provides for a simple and practical construction of couch. Bed section 14 is also provided with mattress springs 17 and when the bed sections are folded as seen in Fig. 2, the sleeping surface of the spring mattress is doubled upon itself, but when unfolded is brought to the same level plane by the arrangement and location of the pivot connections for the sections.

The free end of bed section 14 is supported when down by end projections or rollers 18 which rest and ride upon inner bottom ledge 19 of ends 3, and said rollers 18 also serve as supports for said section when unfolded.

Thus, when frame 6 is unfolded and bed section 14 is raised said projections 18 engage the beveled end of catches 20, one at each end, and finally come to position into the hook portion of the catch. Each catch 20 is pivotally suspended upon the inside face of ends 3 and drops into locking position by gravity, or a spring latch or an equivalent construction may be used instead.

10 Frame 6 and section 14 are bodily removable together from couch frame 2, as pivot lugs 16 merely rest in open sockets 21 mounted upon the inside face of the front post of ends 3. Legs 22 rigidly secured on 15 the free side of bed frame 6 serve to support said frame when unfolded, and said legs stand upright behind pivoted back 5 when the couch is folded and the back 5 is down.

When the parts are folded as seen in Figs. 20 1 and 2 a pivoted member 25 on frame 6 is adapted to lock the seat against upward movement by the engagement of shoulder 26 against the bottom edge of cross rail 27 of frame 2. This locking is especially effective 25 in the event that bedding is folded between the sections as such bedding tends to raise the couch seat more or less according to the thickness or amount of bedding stored away. Member 25 is pivoted to ears on a base plate 30 28 secured to frame 6 and is centrally located between the ends of the frame. A stud or screw 29 on plate 28 projects through an opening in the lower end of member 25 and a spring 30 between the head of said stud or screw and said member provides a spring control for rocking said member within limits on its pivot and a strap 31 attached to the pivot pin passes through an opening in the upper end of member 26 and provides a 40 hand hold for the operator whereby the first pull upon the strap will effect disengagement between shoulder 25 and rail 27 and then bring a positive pull upon frame 6 at its free side to unfold the same.

45 The folding and unfolding of frame 6 automatically folds and unfolds bed section 14 and the operation of converting the couch into a bed and the bed into a couch is simplicity itself. Assuming that the parts are 50 in use as a couch and folded as shown in Figs. 1 and 2, the operator throws the back 5 up out of the way and then grasps strap 30 and raises the free end of frame 6 and swings it back over an arc of half a circle, or from 55 the full line position in Fig. 2 to the dotted line position in Fig. 3. This action inverts seat 7 and brings both bed mattress sections uppermost on the same high plane formerly occupied by the seat and unfolds section 14 60 to make a continuous bed bottom of standard double width. The dotted lines in Fig. 2 illustrate the rearmost position of section 14 and then as frame 6 is carried still onward said section reverses its movement until the 65 respective edges 32 and 33 of frame 6 and

said section meet as seen in full lines Fig. 3. From this position section 14 is bodily carried upward as a rigid part of frame 6 until locking occurs between projections 18 and catches 20.

70 The folding of the parts is just the reverse of unfolding, except that the first movement imparted to section 14 by raising frame 6 is a sliding movement to disengage projections 18 from catches 20.

75 Any other suitable spring bed bottom may be used in lieu of the coiled springs shown, and in some instances this is preferably the case especially where more room for bedding is desired. Frame 6 and bed sections 14 may 80 also be made up of metal instead of wood and in this event either angle iron or tubing would be the preferred form of the material.

75 What I claim is:—

1. In a combined bed and couch, a couch 85 frame, a combined seat and bed frame having a seat portion and a bed bottom respectively arranged upon opposite sides thereof and pivoted to swing from one inverted position to another within said couch frame, 90 fixed legs at the free side of said bed frame, and a separate couch back pivoted to swing upon said couch frame and adapted to overlap and conceal said legs when the bed frame is folded.

95 2. In a combined bed and couch, a couch frame, a combined couch seat and bed frame pivoted on said couch frame and adapted to be inverted, a locking member for said couch seat adapted to engage a part of said couch frame, and a hand strap attached to said member adapted to effect both unlocking and raising of said seat and bed frame.

100 3. In a combined bed and couch, a couch frame and a bed frame pivotally mounted 105 therein, a spring locking member for said bed frame, a hand strap connected with said member, fixed legs for said bed frame, and a swinging couch back upon said couch frame adapted to overlap and conceal said legs and 110 locking member.

105 4. In a combined bed and couch, a couch frame and a bed frame comprising two bed sections pivotally connected and one of said sections having a separable pivot connection with said couch frame, supporting members on said couch frame for said bed section, fixed legs on said bed frame, and a couch back pivoted on said couch frame and adapted to overlap said legs when the bed 120 frame is folded.

115 5. In a combined bed and couch, a main frame having pivot rests at its ends and a swinging spring mattress frame having pivot members removably mounted in said rests, 125 said spring mattress frame consisting of two sections hinged together to fold one upon the other, and a set of rests fixed upon said main frame at different elevations to support the free ends of said lower section when folded 130

and unfolded and adapting said lower member to be inverted and swung outward to give access to the interior of said main frame.

6. In a combined bed and couch, a main frame, a swinging double frame removably and pivotally supported upon said main frame, seat and bed spring mattresses on said double frame, and said main frame having rests at different elevations with which 10 said double frame has separable engagement.

7. In a combined bed and couch, a main frame having a rail across its front and bottom and an invertible bed frame pivoted within the ends of said main frame with its 15 pivots above and spaced apart from said rail, spring bottoms for said bed frame, and said bed frame comprising two sections hinged together and adapted to unfold to the same horizontal plane above said rail and 20 apart therefrom, and free engaging and disengaging rests for said sections adapting either section to be swung freely and to be removed together from the main frame.

8. In a combined bed and couch, a main 25 frame and a two part bed frame pivotally mounted therein, a seat and a bed spring bottom respectively mounted upon opposite

sides of one bed frame part, a supplemental bed frame section having a spring bottom and pivotally connected with said first bed 30 frame part, and supporting members for the free ends of said bed frame sections, in combination with means upon said main frame and said bed frame adapted to lock said sections one upon the other within the main 35 frame.

9. A main frame, a bed frame pivotally mounted therein, a seat on one side and a bed spring bottom on the other side of said bed frame, a supplemental bed section 40 hinged to the bottom side of said bed frame, supports for said sections adapted to permit free movement of said section in respect to said main frame, and a rear rail on said main frame and locking means on said bed 45 frame adapted to engage therewith to prevent upward movement of the free end of said bed frame.

In testimony whereof I sign this specification in the presence of two witnesses.

DAVID T. OWEN.
